ATTORNEY

UNITED STATES PATENT OFFICE

THORNTON W. PRICE, OF NEW BRUNSWICK, NEW JERSEY

MOTOR SUSPENSION

Application filed September 18, 1930. Serial No. 432,775.

This invention relates to a motor suspension, and particularly to a motor suspension of the type designed to absorb the vibratory motion and hum of an operating electric motor or the like, the present invention being in the nature of an improvement upon the structure shown and described in my pending application Serial No. 317,604, filed November 6th, 1928, being now Patent No. 1,780,719, issued November 4th, 1930.

A particular object of the present improvement is to simplify and render more attractive the structure shown in my previous application and also to maintain its durability and improve its effectiveness for its purpose.

A more detailed object is to provide a motor suspension, including a series of tension springs upon which the motor hangs, and a resilient support for said springs made up of material easily obtainable, readily prepared for its purpose and efficient in the performance of its purposes.

A further object is to make up said device as a simple portable element readily movable from place to place.

A further detailed object is to so construct the device that it will possess a desirable degree of resilience throughout for thereby lending to the resilient support of the tension springs employed.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a perspective view of a motor suspension device constructed in accordance with the provisions of this invention, a motor being shown in dotted lines in operative association therewith, and

Fig. 2 is a transverse sectional view upon the plane of line II—II of Fig. 1 to illus-

trate the cross sectional contour of the stock material employed.

Referring to the drawings for describing in detail the structure illustrated therein, the reference characters L, G and H indicate three standards spaced apart equi-distant or otherwise as may be required.

The standards L and G are formed from a single length of material bent into U shape, the standards L and G being the two legs of the U and a connecting portion as 1 of the U being intended to rest flat upon the floor and preferably having apertures or the like as 2 therethrough by which it may be fastened to the floor by screws or other appropriate fastening means.

The standard H is formed as part of a separate piece of material of the same kind as that from which the standards L and G are formed. The piece from which the standard H is formed is bent intermediate its length so that its opposite end portions are substantially at right angles to each other, one of said end portions being the standard H and the other of said end portions, as indicated by the reference character 3 being adapted to lie flat upon the floor and having one or more apertures 4 for accommodating screws or like fastening means. The portion 3 serves to connect the standard H with the standards L and G the extreme end of said portion 3 being welded or otherwise rigidly connected with the portion 1 of the strip from which the standards L and G is formed, as at 5.

The portions 1 and 3 collectively constitute a base for resting squarely and firmly upon the floor and having the standards L and G and H rising from appropriately spaced points thereon.

The upper end of each of the standards is preferably turned or bent inwardly to provide lateral extensions as 6, 7 and 8 projecting in the general direction of a common centre between the several standards. These extensions are formed each with a hole as 9, or other appropriate means, by which the upper ends of a series of coil springs as 10, 11 and 12 may be universally pivotally connected therewith, a convenient method of attachment consisting of having hook shaped

terminals as 13 of said springs engaged through the holes 9 as indicated.

The lower ends of the springs are connected with the motor or with a platform as 14 so as to support said platform suspended therefrom, the connection between the springs and the platform being of a universally pivoted type, for instance of the same general character as the connection between the springs and the extensions 6, 7 and 8. Hooked ends as 15 of the springs may extend through openings as 16 of the platform for this purpose.

It is here noted that the motor platform 15 may be of any desired shape or construction, either as a part of the motor itself, or otherwise, according to preference or convenience in specific cases.

The points of attachment of the springs 20 10, 11 and 12 with the extensions 6, 7 and 8 respectively are at or near the inner ends of said extensions and are hence spaced at one side of the vertical plane of the standards respectively so that any applied weight will 25 tend to bow or bend the standards inwardly toward the common centre, thus placing said standards always under strain.

The openings 16 in the motor platform for receiving the spring ends 15 are preferably 30 arranged in such relation to the standards that the springs extend from said openings in an inclined direction upwardly to their points of attachment with the standards, the inclination of the several springs being such 35 that they converge downwardly from the standards to the platform and thus exert a centering tendency upon the platform serving to hold the platform normally in a properly centered relationship between the standards 40 while at the same time holding the platform in a floating condition freely movable laterally in all directions.

The material from which the standards, and their portions 1 and 3, is formed is preferably 45 of a shallow U cross section throughout, substantially as indicated in the illustration Fig. 2, as by this means a desirable amount of strength and resiliency is secured in a minimum cross sectional area. The material 50 is preferably arranged so that the spaced legs as 17 and 18 thereof face inwardly of the device so that strains applied to the upper ends of the standards, as by the springs 10, 11 and 12, tending to bend the upper 55 ends of said standards inwardly toward each other, will produce a crushing strain longitudinally upon said flanges 17 and 18 and a tension strain upon the web or connecting portion as 19, thereby tending to bow said flanges away from each other.

The character of material employed from which to form the standards may be sheet steel bent into the desired cross section or it may in some cases be ordinary commercial 65 rolled section, and the thickness, cross sec-

tional area and temper of the material varying in different cases according to the size and weight of the motor to be supported.

The openings 2 and 4 by which to fasten the device to a floor or table are preferably 70 arranged close together, that is spaced somewhat from the bottom ends of the standards, so as to offer only negligible opposition to the free flexing of practically the entire length of material from which the standards are 75 formed. Or in some cases the fastening means may be entirely omitted, and in this event the entire length of the material of which the standards is a part is capable of flexing to assist in absorbing the vibratory 80 movements and "hum" of the motor.

The vibratory movement of the motor is impressed first upon the tension springs 10, 11 and 12. From these it passes to the upper 85 ends of the standards and thence is absorbed by said standards. The tension springs are relatively highly resilient but the standards are relatively less resilient. Vibratory movement of the motor is generally absorbed by the tension springs and what is transmitted 90 to the upper ends of the standards is readily absorbed by the standards.

The standards L, G and H constitute vertically disposed leaf springs having laterally turned upper ends from which the upper ends 95 of the tension springs 10, 11 and 12 are suspended, the lower ends of said leaf springs being supported by the portions 1 and 3 which are themselves of a springy character 100 serving to hold the springs in a suitably firm, and at the same time suitably yieldable, normally vertical position.

It will be understood that while the drawings herewith show the device to include only three standards, obviously any number 105 of such standards may be employed grouped about a common centre so that all of the standards will function in the same manner as herein described.

As many changes could be made in this 110 construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters 120 Patent is:

1. A motor suspension comprising a motor platform, a plurality of tension springs by which said motor platform is suspended so as to be freely movable in all lateral directions, and a plurality of substantially vertically disposed leaf springs having lateral turned upper ends from which the upper ends of said tension springs are suspended, together with supporting means for said leaf springs engaging the lower end portions 125 130

- thereof, at least two of said leaf springs and a portion of said supporting means being formed from a single strip of material of U cross section, said strip being bent into U shape. 5
2. A motor suspension comprising a motor platform, a plurality of tension springs by which said motor platform is suspended so as to be freely movable in all lateral directions, and a plurality of substantially vertically disposed leaf springs having upper ends from which the upper ends of said tension springs are suspended, together with supporting means for said leaf springs engaging the lower end portions thereof, at least two of said leaf springs and a portion of said supporting means being formed from a single strip of material bent into U shape so that the legs of the U constitute the two standards 10 and so that the connecting part of the U constitutes the mentioned portion of the supporting means. 15
3. A motor suspension comprising a motor platform, a plurality of tension springs by which said motor platform is suspended so as to be freely movable in all lateral directions, and a plurality of substantially vertically disposed leaf springs having upper ends from which the upper end of said tension springs are suspended, together with supporting means for said leaf springs engaging the lower end portions thereof, at least two of said leaf springs and a portion of said supporting means being formed from 20 a single strip of material bent into U shape so that the legs of the U constitute the two standards and so that the connecting part of the U constitutes the mentioned portion of the supporting means, and another of said leaf springs being formed from a separate strip of material bent so that part of its length constitutes said leaf spring and the remainder of its length is fixed to the connecting portion of the first strip and constitutes another portion of said support. 25
4. A motor suspension comprising a motor platform, a plurality of tension springs by which said motor platform is suspended so as to be freely movable in all lateral directions, and a plurality of substantially vertically disposed leaf springs having upper ends from which the upper end of said tension springs are suspended, together with supporting means for said leaf springs engaging the lower end portions thereof, at least two of said leaf springs and a portion of said supporting means being formed from a single strip of material bent into U shape so that the legs of the U constitute the two standards and so that the connecting part of the U constitutes the mentioned portion of the supporting means, and another of said leaf springs being formed from a separate strip of material bent so that part of its length constitutes said leaf spring and the 30 remainder of its length is fixed to the connecting portion of the first strip and constitutes another portion of said support. 35
- In testimony whereof I affix my signature. 70
